UNITED STATES PATENT OFFICE.

CARL KRUG, OF FRANKFORT-ON-THE-MAIN, MAINKUR, GERMANY.

ABRADING-DISK.

1,139,541.

Specification of Letters Patent. Patented May 18, 1915.

Application filed June 17, 1913. Serial No. 774,262.

To all whom it may concern:

Be it known that I, CARL KRUG, a subject of the German Emperor, and resident of Frankfort-on-the-Main, Mainkur, Germany, 5 have invented a certain new and useful Improvement in Abrading-Disks, of which the following is a specification.

Abrading disks made in thin layers and particularly those of large diameter such as 10 are used in abrading machines with rotary steel disks are liable to become broken in transport even when very carefully packed. Apart from the question of damage, the packing having regard to its bulkiness, costs 15 a great deal compared to the cost of the disk itself. In the abrading disk forming the subject of the present invention this disadvantage is overcome, by dividing the abrading layer into parts, and securing the same 20 on a flexible foundation holding the parts together. By so dividing the disk it can be folded into an easily transportable and unbreakable form.

Two embodiments of the invention are 25 illustrated in the accompanying drawing, in which—

Figure 1 is a plan and Fig. 2 a section with the parts in extended position, while Fig. 3 is a view of the folded disk in one 30 embodiment; Fig. 4 is a plan and Fig. 5 a section with the parts in extended position while Fig. 6 is a view of the folded disk in another embodiment.

In accordance with the embodiment illustrated in Figs. 1 to 3, the disk, which is formed with a central orifice, *o*, consists in known manner of the abrading layer *a*, which in the example shown is divided by 35 rectilinear cuts or furrows *b* into two parts 40 1 and 2, and secured, for example cemented, to the usual foundation of fibrous material *f*.

In the embodiment illustrated in Figs. 4 to 6, the abrading layer consists of three parts 1, 2 and 3 formed by furrows *b* and *d*, and is secured to the usual foundation of 45 fibrous material *f*, for example by means of a layer of cement.

For despatching the disk formed in accordance with the first embodiment, the part 2 is folded, in the manner indicated in Fig. 50 3 on the part 1, so that the disk is reduced to half of its original dimensions.

For despatching a disk as shown in Fig. 4, the parts 1 and 3 are folded on the part 2 in the manner indicated in Fig. 6 so that 55 the size of the disk is reduced to that of the part 2.

In each case a considerable increase in the resistance to fracture is obtained and much better use is made of the packing space 60 available with a consequent reduction in the cost of packing and of transport. The subdivision of the disk has not been found to impair its strength in abrading.

Having described my invention I declare 65 that what I claim and desire to secure by Letters Patent of the United States is:—

Abrading disk comprising in combination, an abrading layer, a foundation of fibrous material to which said layer is cemented, 70 both provided with a central orifice, said abrading layer being provided with a central crease for allowing the folding of the disk, substantially as described and for the 75 purpose set forth.

In testimony whereof I have signed my name to this specification in the presence of two subscribing witnesses.

CARL KRUG.
